UNITED STATES PATENT OFFICE.

JOHN EDWARD WRIGHT, OF PITTSBURGH, PENNSYLVANIA.

PRINTING-TELEGRAPH.

1,090,365.

Specification of Letters Patent. Patented Mar. 17, 1914.

Application filed December 9, 1912. Serial No. 735,682.

To all whom it may concern:

Be it known that I, JOHN EDWARD WRIGHT, a citizen of the United States, residing at Pittsburgh, in the county of Allegheny and State of Pennsylvania, have invented certain new and useful Improvements in Printing-Telegraphs, of which the following is a full, clear, and exact description.

10 The improvements constituting the invention which forms the subject matter of this application, are embodied in a combination of mechanisms capable of independent operation or control, but co-operatively related 15 and adapted to print in column form upon a sheet of paper, letters and characters corresponding to definite combinations of electrical impulses transmitted over a telegraph line, and to effect the spacing, paper feed and 20 other operations necessary for such purpose and usually performed by a unitary device known as a printing telegraph receiver or machine.

The primary object of my invention is, in 25 general, to provide a printing mechanism capable of rapid and accurate response to current impulses transmitted over long circuits where the line conditions are such as to materially, and often seriously limit the 30 speed and efficiency of the instruments heretofore devised and used for this purpose, but in the attainment of this object I have invented and devised features which not only contribute to the more efficient operation of 35 the particular system of which this instrument constitutes a member, but which are also distinctive in themselves as novel and useful elements in telegraphic printing and signaling machines in general.

40 My improved instrument contains means for supporting a sheet of paper of indefinite length, and a type wheel in the form of an elongated cylinder having a plurality of rows of letters and characters arranged, in 45 the present instance, in ten vertical columns, and comprises as its more essential elements, novel in construction and function, electrically actuated devices capable of independent and non-interfering and hence simultaneous 50 operation and control which may be generally defined as follows: (1) Mechanism for turning a type wheel to bring any one of, say, the odd numbered character columns in line with the printing position. (2) 55 Mechanism for shifting the type wheel

around its axis through the space of a single column to bring an even numbered character column in line with the printing position. (3) Mechanism for moving the type wheel longitudinally to bring any horizontal row 60 of characters in line with the printing position.

In addition to the above, I have devised and employ means for spacing between characters, for feeding the paper, for restoring 65 the type wheel to its normal position at any point of its line of travel, for restoring the type wheel to its initial position to begin a line, and for effecting the other operations incident to apparatus of this character, all 70 of which from the nature of their construction and function may be best described by reference to the accompanying drawings in which—

Figure 1 is a front view in elevation of 75 the completely assembled elements making up the improved instrument. Fig. 2 is a side elevation of the same, as viewed from the left of Fig. 1. Fig. 3 is a top plan and part sectional view of the complete device. 80 Fig. 4 is a vertical sectional elevation looking toward the right of Fig. 1. Fig. 5 is a similar view looking toward the left of Fig. 1. Fig. 6 is an end elevation looking toward the left of Fig. 1. Fig. 7 is a sectional detail 85 on the line α — α of Fig. 6. Fig. 8 is a view in elevation of parts associated with the magnet which controls the impression devices. Fig. 9 is a diagram of the circuit connections showing the relations of the several instrumentalities. Figs. 10 and 11 illustrate details of mechanism shown in elevation in Fig. 2.

The various parts comprising the apparatus are attached to and supported by a substantial frame composed of a base plate 1, and side plates 2, 3. Extending horizontally between these plates in the upper portion of the instrument is a paper feed roller consisting of a shaft 4 carrying at its ends cylinders 5, 5, having roughened or rubber faces, and intermediate disks 6, 6. Presser rolls 7, 7, spring actuated and carried by arms pivoted to a shaft 8 bear upon the roughened surfaces of the cylinders 5, 5. 100 The paper from a suitable supply reel is carried upward around guide rollers or disks 9, supported by spring actuated arms 10, then between the platen and the type wheel, hereinafter described, and between the 110

presser rollers 7 and the cylinders 5 by which it is gripped and fed by the rotation of the latter.

The details of the type wheel and its accessories are best shown in Fig. 4. The type wheel 11, in the form of a copper cylinder, slides freely on a vertical spindle 12 triangular in cross-section and rotatably mounted in a frame or carriage 13, which has as its three points of support, the horizontal spindles 14, 15, each triangular in cross-section, and a rigid bar 16, in a slot in which projects an extension of tail piece 17 of the type wheel carriage carrying at its end an anti-friction roller 18. The spindle 14 passes through a triangular opening in a sleeve 19, see Fig. 1, which has a bearing in an arm 20 extending horizontally from the carriage 13. The spindle 15 in like manner, passes through a triangular opening in a sleeve 21 having a bearing in an arm 22, rigidly attached to the carriage 13. The latter is thus held firmly against lateral movement, but is free to move longitudinally along its three points of support, which latter movement is imparted to it by a screw shaft 23 passing through a geared nut in a projection 24 on the inner surface of the forward side of the carriage. Vertical movement is imparted to the type wheel by a rack-bar 25, sliding in guides on the carriage 13 and having a lateral arm 26 to which the type wheel is connected in a manner not to interfere with its free rotation. A gear wheel 27, mounted fixedly on the sleeve 19, and rotated by the triangular shaft 14, engages the rack bar 25 and when turned, raises the latter and with it the type wheel, to a position corresponding to the extent of rotation of the gear wheel. Rotary motion is imparted to the type wheel by a beveled gear wheel 28, mounted on the sleeve 21 and meshing with a beveled pinion 28^a, secured to the lower end of the spindle 12 carrying the type wheel. The gear 28 is turned by the triangular shaft 15, and the extent of rotary movement imparted to the type wheel thereby corresponds to the arc through which said shaft is turned.

In the type wheel carriage there are mounted two horizontal and parallel sliding rods 29 secured to and supporting an upright 30, provided with notches corresponding in position to the five vertical positions of the type wheel. Extending horizontally from the upright 30 is a rack bar 31 in gear with an elongated pinion 32, journaled in the side plates 2 and 3 of the instrument. A fork or pawl 32^a, carried by a spring actuated bolt 33, sliding horizontally in guides on the arm 26 is forced forward by a movement of the upright 30 into engagement with a ratchet wheel 34 on the type wheel, and at the same time its beveled end seeks the lowest point in the adjacent notch in said

upright, so that the type wheel during such engagement is locked against both rotary and vertical movement and with a given selected character exactly in the printing position.

A sheet metal plate 35 is secured to the carriage 13, and extends upwardly back of the type wheel. Near its upper end this plate is bent and perforated, as shown at 36, Fig. 4, so as to expose a portion of the raised characters on the type wheel. This opening defines the printing position, and to effect an impression from any character type that may be presented at such opening a platen 37 extending across the instrument and mounted by arms 38 on a rock shaft 39, is oscillated at the proper instant and caused to force the paper against the positioned character type.

From the above description it will be seen that if the type wheel be rotated in its initial position, shown in Fig. 4, all of the characters in the upper row may be brought successively to the printing position, and that if, either with or without rotation, as the case may be, it be raised to align the four lower rows of characters with the printing position any other character on the wheel may be brought to the proper point for impression. It will be further observed that the devices which rotate and raise the wheel may be operated independently and either successively or simultaneously. It remains, therefore, to describe the mechanisms which effect or control the operation of these devices.

Referring to Figs. 6 and 7: An electromagnet or double solenoid 40 is secured to the side plate 2 and provided with a plunger or long stroke armature 41. A vertical slide rod 42 is connected at its lower end with the yoke of the armature by a spiral spring 43 and head 44, its upper end being pivotally connected to an arm 45 of a rock shaft carrying a toothed segmental arm 46. A spiral spring 47 tends to raise the arm 46 and depress the rod 42. The segmental arm 46 engages with a pinion 48 on a short shaft 49 (see Figs. 1 and 3) having bearings in the side plate 2 and a bracket arm 50 secured thereto, respectively, and when the magnet 40 is energized the raising of the rod 43 and swinging of arm 46 rotates the shaft 49 and with it the triangular spindle 14, which, although journaled on pointed pivot screws, is connected to shaft 49 by means of a spring dog 51, secured to the shafts 14 and 49, respectively, as shown in detail in Fig. 3. This connection is typical of any form of yielding connection which will transmit the rotation of one shaft to the other accurately, but without shock. The operation of these devices, as has been stated above, results in a lifting of the type wheel, the extent of lift obviously corresponding to the

are through which the shafts 49 and 14 are turned. The means for controlling and limiting these movements are as follows: Secured to the side plate 2 is a U-shaped bracket 52 to the lower arm of which three blades 53, 54 and 55, are pivoted side by side and extend upward through a slot in the upper arm. Springs 56 act upon the said blades tending to maintain their upper end 5 in engagement with the forward or outer side of the slot through which they project. A fourth blade or stop 57 of the full width of the slot is fixedly secured to the bracket for a purpose to be described. Three electro-magnets 58, 59 and 60, are mounted on the side plate 2, and each is provided with an armature carrying a finger, the end of which is adapted to engage with and oscillate one of the blades when its magnet is energized. A rack bar 61 mounted to slide horizontally in suitable guides on the side plate 2 is engaged by a pinion 62 on the shaft 49 so that when the magnet 40 is energized and the arm 46 turned, the rack bar 20 61 will be forced forward to a corresponding extent. Normally, the blades 53, 54 and 55, lie out of the path of movement of the rack bar 61, which path is limited only by the fixed stop 57, but when one of the magnets 58, 59 or 60 is energized, the blade corresponding thereto is shifted into the path of the rack bar 61, thus limiting the throw of the latter to less than the normal. These parts are so proportioned that when one of the magnets 58, 59 or 60 is energized the rack bar 61 operated by the solenoid 40 completes its full normal throw and raises the type wheel to bring its lowermost row of characters in alinement with the printing position. If, on the other hand, any one of the said magnets, as 60, be energized, then by the interposition of the blade 55 in the path of the bar 61 the type wheel will be raised but three steps, instead of four, and 45 so on. Turning now to the opposite side of the instrument, there is mounted on plate 3 a double solenoid magnet 63 with a long throw armature and a sliding bar 64 spring connected therewith, these elements being practical counterparts of the magnet 40 and its appurtenances above described. The bar 64 operates, in like manner, a segmental arm 65 against a spring 66 which transmits rotary motion through a short shaft 67 to the triangular spindle 15. A rack bar 68 is also reciprocated by a pinion on the shaft 67 and limited in its throw by four blades, one fixed and three movable, the latter engaged respectively by the armatures of three magnets 69, 70 and 71, and from the foregoing it will be understood that if none of these magnets is energized the rack bar 68 completes its full throw and the type wheel is turned through eight-tenths of a complete 55 revolution from its initial position of rest.

The energizing of magnet 71 limits the movement of the type wheel to six-tenths, of magnet 70 to four-tenths and of magnet 69 to two-tenths of a revolution. Thus, by means of the devices just described any one 70 of the five odd numbered vertical columns of characters on the type wheel may be brought into alinement with the printing position. To bring any of the intermediate or even numbered columns of characters into position to print, the type wheel is advanced or shifted horizontally through the space of one vertical row from either its initial or any position to which it may be turned by the magnet 72, and this operation may be 75 effected either before, after or during the operation of the magnet 63, and its appurtenances by a mechanism which is best shown in Fig. 2. This comprises a solenoid magnet 72 with an armature 73 supported above and partly out of the coils by a spring seated 80 rod 74. When, therefore, the magnet is energized the rod 74 is forced downward. To the lower portion of the rod is secured a block 75 with a beveled face against which 85 bears a roller 76 on a stud mounted on a bar 77. The blades 53, 54 and 55, which limit the movement of the rack bar 61, that lifts the type wheel, have been described as pivoted to a stationary bracket, but the corresponding blades which limit the movement of the rack bar 68 that operates to turn the type wheel, are pivoted to a sliding frame to which the bar 77 is attached, so that when magnet 72 is energized, this frame will be 90 95 shifted by a spring 78, toward the left, Fig. 2, but not sufficiently to carry the blades out of the path of their appropriate armatures. The rack bar 68 carries a bar 79 with a toe 98 100 that engages a stop on the sliding frame 105 so that when the latter is shifted the rack bar will be carried forward correspondingly, a distance which is just sufficient to impart to the triangular spindle 15 a movement that advances the type wheel one-tenth of a revolution, or through the space occupied by a single vertical column of characters. To print, therefore, a character in the first or initial row, or the third, fifth or any odd numbered row, magnet 63 with either none 110 115 or one of the magnets 69, 70, 71, is operated. To print from the second row, the magnet 72 alone is energized, or to print from any other even numbered row the magnet 63 with either none or one of the magnets 69, 70 or 71 is also energized.

In addition to the instrumentalities above set forth for setting the type wheel to print any desired character thereon, I employ various other devices which are necessary or desirable in the operation of the instrument. One of these is a means for locking the type wheel when adjusted to position and immediately prior to the operation of printing a character. This comprises an electro-mag- 125 130

net or solenoid 81, armature 82, and rod 83, connected thereto, that operates to oscillate a pivoted arm 84 carrying a segmental gear that meshes with the elongated pinion 32, 5 heretofore described. The operation of the magnet 81 is so timed that the type wheel is set in position before the rack bar 31 is forced forward to bring the upright 30 in engagement with the locking bolt 33.

10 Another accessory is the means for advancing the type wheel carriage step by step after each impression, to space for characters. This comprises a beveled wheel 85, mounted on a shaft 86, and gearing with a 15 beveled pinion 87 on a short counter-shaft 88, carrying at its opposite end a beveled pinion 89 meshing with a similar gear 90 on the screw shaft 23. The gear wheel 85 is rotated step by step by means of a ratchet 20 wheel 91 on the shaft 86 with which engages a pawl 92 carried by a pivoted lever 93 which is operated by engagement with a bar 94 sliding in guides under the base plate of 25 the instrument and connected with the armature of a feed magnet 95. With each movement of the armature of this magnet the type wheel carriages, through the gearing described, is advanced one character space, and in order to provide for the return of the 30 carriage from the end or any other point in a line, the shaft 23 is extended to project through the side 3 of the instrument, where it carries a pinion 96, meshing with a barrel 97^a that stores up the force of a coiled spring 35 contained therein and operates to rotate the shaft 23 backward when the latter is released. This release is effected by a magnet 97, having a spring actuated armature 98 connected by a rod 99 with an arm 100 fixed 40 to a short rock shaft 101 carrying a retaining pawl 102 engaging with the ratchet wheel 91. Normally the pawl 102 rides over the teeth of the wheel 91 as the latter is advanced, but prevents its backward movement. When, however, the magnet 97 is energized the pawl is lifted from wheel 91 and the type wheel carriage is brought back toward the starting position. In order to insure a complete return of the carriage, a 45 spring actuated lever 103, pivoted to the side plate 3, is made to bear against the side of the free end of the pawl 102. A shoulder 104 is cut in the lever 103 and with this the pawl 102 engages when, by the operation of 50 the magnet 97, it is lifted fully from the ratchet wheel 91. When the type wheel carriage, therefore, has been released by the action of magnet 97 it remains free until it has been brought fully home, when it strikes the 55 end 105 of lever 103 and disengages the latter from the pawl 102.

The printing is effected, as has been in part described, by the oscillation of the platen 37, which forces the paper sheet

against the selected and positioned character on the type wheel. The rock shaft 39 carrying the platen may be operated for this purpose by a special magnet, but inasmuch as the locking of the type wheel must always precede the operation of printing, 70 the movement of the means for effecting the locking of the wheel is conveniently availed of for operating the platen. I accomplish this by the means shown in Fig. 4. A rod 106 is mounted to slide in guides on the side 75 plate 2 and carries a rack bar 107, that engages with the pinion 32. The rod 106 also carries a stop 108, adjacent to the platen 37, so that when the pinion 32 is rotated by the magnet 81 and segmental arm 84, the rod 80 106 is pulled forward, thereby engaging the platen through the stop 108 and forcing it against the paper.

The paper is fed for line spacing by an electro-magnet 109, the armature of which 85 operates a pawl 110, engaging with a ratchet wheel 111 on the shaft 4, through the instrumentality of a spring actuated lever 112, a connecting rod 113, and a pivoted lever 114 carrying the said pawl 110, as shown in 90 Fig. 5.

Each of the mechanisms heretofore described as the means for effecting the various operations necessary for adjusting and locking the type wheel, securing the impressions, advancing the type wheel carriage for character spacing, returning the carriage and feeding the paper for line spacing, might be included in a separate and independent circuit and the instrument operated 95 by completing the circuits at the proper intervals of time. Practical considerations, however, due in part to the relations which certain of the operations bear to each other, render it desirable to provide special means 100 for the operation and control of the various mechanisms and in Fig. 9 the means which I have devised for this purpose are shown in diagram. Before proceeding to a description of the diagram, however, it is necessary 110 to explain the construction and function of certain devices not heretofore referred to.

In Figs. 1 and 3, two small electro-magnets, 115 and 116, shown as mounted on the base plate 1, are provided with spring actuated armatures, 117 and 118, which constitute circuit closers, the stationary terminals of which are supported in an insulating cross bar 119.

In Figs. 3 and 8 is shown what may conveniently be termed a timing magnet 120, that is to say a magnet having a torsional or long throw armature 121, which requires an appreciable interval of time to complete its full movement when the cores by which it is 120 attracted are energized. This armature carries an arm 122, which, near the end of its throw, encounters a pivoted lever 123

carrying a contact spring 124, and forces the latter against a fixed stop 125 in its path, and thereby completes an electric circuit.

In Figs. 3 and 4, there is shown a magnet 126 having a spring actuated armature 127 to which is connected, by means of a stop 129 and a spring 130, a rod 128 that extends downward through the base of the instrument, and engages the end of an arm 131, 10 on a rock shaft 132, mounted in bearings on and underneath the base plate 1. When the magnet 126 is energized it acts to depress the arm 131 and impart to the rock shaft 132 a partial rotation against the force of a 15 spring. Another arm 165, fixed rigidly to the rock shaft 132, lies immediately under the end of the rod 83 of magnet 81 which locks the type wheel, and is depressed whenever said magnet 81 is fully energized. The 20 rock shaft 132, therefore, will be partially turned by the operation of either magnet 126 or magnet 81, but from the nature of the connections shown it is evident that its movement by one magnet will not be interfered with by the other. An arm 133, 25 extending rigidly from the rock shaft 132, rides against a spring actuated latch 134, pivoted to the under side of the base 1, as shown in Figs. 1 and 4, so that when the 30 rock shaft is turned and the arm 133 depressed, the latter is engaged by the latch and held down until released by the withdrawal of the latter. Such release is effected by a pivoted lever 135 engaging at one 35 end with the latch 134 and at the other with a stop 136 on the rod 94, which, when shifted by the magnet 95, operates to advance the type wheel to space for characters. On the forward end of the rock shaft 132 is an arm 40 137 extending upwardly through the base plate 1 and carrying at its end an insulated stud 138. In the path of this stud are two normally separated contact levers 139 and 140, which by the engagement of the stud 45 with lever 139 are brought together to complete an electric circuit.

In Figs. 2 and 5 a device for changing the paper feed from single to double line spacing is shown. This consists of a bent 50 lever 141, pivoted to the side plate 3, and having a stud that projects through a slot in said plate and lies under one arm of the bell crank lever 110 constituting the pawl that engages with the ratchet wheel 111 of the paper roll. The lever 141 is acted upon by a spring actuated lever 142, having a cam 55 projection 143 to hold the first named lever in either of its two normal positions by engaging with a pin 144 thereon. By shifting the lever 141 the throw of the pawl is varied 60 in a manner that is well understood.

Referring now to Fig. 9: A plurality of local circuits is provided in the instrument by the proper number and disposition of in-

sulated conductors and terminals, the latter 65 in the commercial instrument, being conveniently placed on the base plate 1 in the rear of the working parts. I have shown nineteen of these terminal plates, but a greater or less number may be employed if 70 desired to meet special conditions or effect special results, and to distinguish them they are numbered consecutively from 145 to 163. From each of the terminal plates 146 to 159 75 inclusive, a circuit connection or wire is shown, which, if carried to ground, will effect the operation hereinafter described. These connections, to correspond with those of the translator, are designated by the letters *a* to *n*, respectively. The terminal 160 80 is shown conventionally as directly connected to earth. Assume then, for the purposes of illustration, that a battery 164, or other local source of electrical energy for the operation of the instrument, is connected to the terminal plate 145 and to ground, respectively. It follows from the circuit connections and apparatus illustrated that if plate 146 be 85 grounded, a current starting from battery 164 will pass to the magnet 115, thence through magnet 63, thence through magnet 69, and thence to ground through terminal plate 146. From previous explanations it will be understood that the result will be the operation of the type wheel turning magnet, 90 the drive of which will be limited by magnet 69, which acts somewhat quicker, to one step or two column spaces, and the character at the top of the third vertical column will be presented in the printing position. It 95 will also result that magnet 115 attracting its armature 117 will close a branch circuit from the battery through timing magnet 120, which in turn closes the circuit of the type wheel locking and printing magnet 81, 100 which latter by the depression of the rod 83 imparts a partial rotation to the rock shaft 132, causing the latter to engage with latch 134 and closing the contact between 139 and 140. This closure completes a branch circuit 105 from the battery to the cross-feed magnet 95 which in its operation of advancing the type wheel carriage one step after the impression has been taken, operates lever 115 110 and releases the latch engaging the arm 133 of the rock shaft. This completes the operation, the type wheel having received a turning movement of one step or two column spaces, the character printed and the cross-feed effected.

It is required in the system for which this instrument was designed and with which it, as organized according to the above description, is intended to be used, that, after each 115 operation, effected by grounding any one or more of the terminal plates, a path for current to an electro-magnet in another part of the system be closed, bringing about what is 120 125

known as the clearing of the instrument which controls the operation of the printing apparatus.

It has been explained that whenever either 5 the type wheel locking magnet 81, or the timing magnet 120, or both, are energized, the contact points 139 and 140, Fig. 1, are brought into engagement and so maintained by the arm 133 engaging with the latch 134. 10 This operation closes the circuit from the battery 164 to ground through the cross feed magnet 95, which, at the end of its operation, releases the latch 134 and breaks the circuit between points 139 and 140. It will 15 be observed, however, that by completing the circuit to ground through magnet 95, the battery 164 is also connected to terminal 155, which latter is arbitrarily selected for the circuit that includes the clearing magnet 20 above referred to, and which is therefore operated whenever the cross feed magnet 95 is energized. It will be further observed that when the paper feed magnet 109 is energized, either alone, or in conjunction with 25 other magnets of the apparatus, it operates through the instrumentality of any suitable connection, such as shown in Figs. 3 and 5, a circuit controller 167, which connects the battery 164 with terminal 155. Thus it follows, that whatever devices may be included 30 in the circuit continued to ground from terminal 155, they will be operated not only when the cross feed magnet 95, but also when the paper feed magnet 109 is energized. 35 If terminal plate 147 be grounded the same operations will take place except that magnet 70, instead of 69, is energized, which results in the type wheel being turned to an arc including four character column 40 spaces. In like manner, the grounding of terminal 148 brings the seventh column on the type wheel into printing position, and so on. The grounding of plate 150 causes current to flow through the type wheel shift 45 magnet 72, which, as has been described, advances the type wheel one column space, bringing the second column of characters to the printing position when no other turning movement has been imparted to the type 50 wheel. The grounding of terminal plate 151 causes current to pass to the driving magnet 40 and also the magnet 58 which lifts the type wheel one step or stage and brings the 55 second row of characters to the printing position, all of the other operations heretofore described, except that effected by the type wheel shift magnet, being repeated. In like manner the grounding of plate 152, lifts 60 the type wheel to bring the third horizontal row of characters to the printing position, and so on, and from the description of the apparatus heretofore given it will be evident that any two or more of the above described 65 operations may be effected simultaneously. 70 That is to say, by grounding the proper ter-

75 minal plates the type wheel may be simultaneously lifted, turned and shifted, to bring any desired character thereon into position to be printed. Terminal 155, as has been above stated, is arbitrarily selected to complete a path for current to pass to the clearing magnet in another part of the circuit at the same time that it also passes from the battery to the cross feed magnet. If the terminal plate 156 be grounded, the current 75 passes to control magnet 116, which closes the circuit through magnet 127 which latter, as above described, closes the circuit to the cross feed magnet by bringing together the contact points 139 and 140, and effects no 80 other operation besides spacing except that of clearing. If terminal plate 157 be grounded, the paper feed magnet 109 alone is operated so that the paper may be fed line by line without actuating any of the other 85 devices. Inasmuch as this operation however requires the transmission of a clearing current the magnet 109 operates a circuit closer 167 which completes the battery connection to plate 155, which circuit is interrupted by a cessation of the current impulse through the paper feed magnet. If terminal 158 be grounded, the magnet 97 that releases the type wheel carriage and permits it to 90 return to the position to begin a line is 95 operated. The closure of this circuit however also energizes the paper feed magnet 109 which in turn closes a circuit to terminal 155, whereby the clearing operation is effected. When contact plate 159 is grounded a 100 path for the current is completed from the battery through control magnet 116, and a signaling device 166, which is used for transmitting to the sending operator at the receiving station a conventional signal. Control magnet 116 completes a circuit through the magnet 127, by means of which the clearing operation heretofore described is effected. 105

110 Terminal 160, while not so marked, is a general ground for the apparatus and wherever the conventional lines indicating a ground are used, connection with the terminal plate 160 is assumed. Terminal plates 161, 162 and 163 are in practice utilized for purposes which have no direct bearing on the features of novelty upon which the present application is based, and require no further description herein. 115

120 It will be noted that the circuit of control magnet 115 is common to both the turning and lifting magnets 40 and 63, and that the circuit controlled by it operates the timing magnet 120, which latter is purposely comparatively slow in operation in order to permit the type wheel to reach the desired position before it is locked and the impression taken. As soon as these last named operations have been accomplished, the locking and printing magnet 81 operates the circuit 125 controlling contacts 139 and 140, which 130

complete the circuit to the cross feed magnet 95. The cross feed or spacing is virtually the final step in any series of operations as its action is the final stroke in the printing 5 of a character. At the end of the movement or operation of the cross feed magnet, the contact between 139 and 140 is broken, the ground is lifted from whatever circuits have just been used and the machine and the apparatus which controls its operation are 10 ready for the next character or whatever other operation may be desired.

Although it forms no part of the invention subject of the present application, and 15 is not therefore described in detail, there is employed as the means for controlling the operations above described a device which for convenience may be termed a translator, the operation of which is dependent upon 20 current impulses transmitted in definite time relations over a line, and it necessarily follows that in the practical operation of the system certain mutual relations must be maintained between this translator and the 25 apparatus herein described which are more fully elaborated in an application for the former instrument filed January 22, 1913, Serial No. 743,511, but which having to do with the control of the devices herein de- 30 scribed and not with their construction are not necessary to an understanding of the present device.

What I claim is:

1. In a printing telegraph instrument, the 35 combination with a type-wheel and a carriage therefor, of rotary spindles in gear with the type-wheel, one adapted to impart rotary and the other longitudinal movement thereto, of rack bars capable of rectilinear 40 movement and geared with the spindles, electro-magnets and armatures for imparting movement to said rack bars, stops in the paths of said bars, and electro-magnets for controlling the operation of said stops.

2. In a column printing telegraph instrument, the combination with a type-wheel, a carriage therefor and feeding means for advancing the carriage, of driving electro-magnets and intermediate connections be- 50 tween the same and the type-wheel, one adapted to impart rotary and the other longitudinal movement thereto, stops for limiting the extent of the movement imparted by such connections, and electro- 55 magnets for controlling the operation of said stops.

3. In a printing telegraph instrument, the combination with a type wheel, of a driving electro-magnet and intermediate connections 60 for imparting rotary movements of varying extent and in a given direction from its initial position, to said type wheel, stops for limiting and determining the extent of such movements, electro-magnets for controlling 65 the operation of the stops, and means for

imparting to the type wheel a rotary movement of definite extent and in the same direction, independently of the driving and stop controlling magnets.

4. In a printing telegraph instrument, the 70 combination with a rotary type wheel, of a spindle in gear therewith and adapted to rotate the same, a driving electro-magnet and armature geared to and adapted to rotate the spindle in a given direction, electrically controlled stops for limiting the rotation of the spindle to arcs of varying lengths, and means for imparting to said spindle rotation in the same direction through an arc of fixed length independently of the driving 80 magnet and electrically controlled stops.

5. In a printing telegraph instrument, the combination with a type-wheel, of a driving electro-magnet and intermediate connections for imparting rotary movement to said type 85 wheel from its initial position, stops for limiting such movement to arcs that include two character columns or multiples thereof, electro-magnets for controlling the operation of the stops and means for imparting to the 90 type wheel from any position a rotary movement through an arc including one character column only, independently of the driving and stop controlling magnets.

6. In a printing telegraph instrument, the 95 combination with a type wheel and a carriage therefor, of rotary spindles in gear with the type wheel, one adapted to impart rotary and the other longitudinal movement thereto, of electro-magnets and armatures 100 for imparting rotation to said spindles, means for limiting the extent of such rotation and electro-magnets for controlling the operation of said means.

7. In a printing telegraph instrument, the 105 combination with a type wheel and supports therefor, independently controlled driving magnets and intermediate connections, one for imparting a rotary and the other longitudinal movement to the type wheel, stops 110 for limiting the extent of the movement imparted by such connections and electro-magnets in circuits common to the two driving magnets respectively for controlling the operation of said stops.

8. The non-interfering means for simultaneously imparting rotary and longitudinal movement to the type wheel of a printing telegraph instrument, comprising in combination with the type wheel and its supports, two rotary spindles one adapted to impart rotary motion to the type wheel support and the other longitudinal movement to the type wheel on its support, driving electro-magnets and armatures geared with the two spindles 120 respectively, stops for limiting the extent of the rotary movement imparted to the spindles and electro-magnets for controlling the operation of said stops.

9. In a printing telegraph instrument, the 130

combination with a type wheel capable of rotary movement about its axis and longitudinal movement thereon, of non-interfering means for simultaneously imparting rotary and longitudinal movements of varying extent and an additional rotary movement of definite extent thereto.

10. In a printing telegraph instrument, the combination with a longitudinally movable type wheel carriage and type wheel mounted thereon, of a locking device for the type wheel, a pinion for operating said locking device and coextensive in length with the travel of the carriage and an electro-

15 magnet and armature for imparting rotation to said pinion.

11. In a printing telegraph instrument, the combination with a longitudinally movable type wheel carriage and type wheel mounted thereon, of a locking device for the type wheel, a pinion for operating said locking device, and coextensive in length with the travel of the carriage, an impression mechanism in gear with said pinion, and an electro-magnet and armature for imparting rotary motion to the pinion.

12. In a printing telegraph instrument, the combination with a type wheel, of a driving electro-magnet and intermediate connections for imparting rotary movement to the type wheel, electrically controlled stops for varying and limiting the extent of such movement, and means for shifting the position of said stops and advancing the type wheel through an arc of definite extent independently of the action of the driving magnet.

13. In a printing telegraph instrument, the combination with a type wheel and means for adjusting the same to bring any desired character thereon to the printing position of a slow acting or timing magnet in a circuit controlled by the type wheel adjusting means, and printing and spacing mechanism adapted to be operated by the timing magnet.

14. The mechanism for imparting rotary movements of varying extent to a type wheel, comprising in combination a driving magnet and armature, a rack bar reciprocated by the armature and in gear with the type wheel, a sliding frame, a series of levers pivoted thereto and adapted to oscillate across the path of the rack bar, electromagnets for operating said levers and an electromagnet for shifting the sliding frame and moving the rack bar connected therewith independently of the driving magnet.

15. In a printing telegraph instrument, the combination with a type wheel, of mechanism, for adjusting the same to bring any desired character thereon to the printing position, impression mechanism and feed mechanism, each of said mechanisms including an electromagnet in a circuit local to the instrument, a clearing circuit and means for completing the same dependent upon the operation of any of said mechanisms.

In testimony whereof I affix my signature in the presence of two subscribing witnesses.

JOHN EDWARD WRIGHT.
